UNITED STATES PATENT OFFICE.

CHARLES H. ATKINS, OF SPRINGFIELD, MASSACHUSETTS.

THERMOSTATIC STEAM-TRAP.

SPECIFICATION forming part of Letters Patent No. 739,279, dated September 22, 1903.

Application filed March 3, 1902. Serial No. 96,861. (No model.)

To all whom it may concern:

Be it known that I, CHARLES H. ATKINS, of Springfield, Hampden county, State of Massachusetts, have invented an Improvement in 5 Thermostatic Steam-Traps, of which the following is a specification.

More particularly, my invention relates to that class of valve devices or traps used in steam heating apparatus in which the thoroughfare or valve passage-way is controlled by thermostatic action through the medium of a thermostatically-actuated part which controls the valve-piece to open the passage-way when subjected to air or water of condensation and to close it when subjected to uncondensed steam. As now generally constructed such valves employ an expanding plug formed of a composition of matter 15 highly susceptible to variations in temperature, but owing to the limitation in the length of the plug the effective movement is very slight, and it has been difficult to obtain sufficient movement in the valve-piece to properly control the thoroughfare.

It is the object of my invention to increase 25 the effective movement imparted to the valve-piece by the thermostatically-actuated part or member, so that a very small movement in the latter will produce a sufficiently large 30 movement in the former, thus enabling the thoroughfare to be opened to a much greater extent than is now possible. This object I accomplish by interposing a multiplying power-transmitting connection between the 35 expanding member and the valve-piece, which may be so constructed as to produce practically any desired increase in the movement of the valve-piece.

My invention also embraces certain improvements in the manner of assembling and 40 combining the parts, whereby the thermostatically-controlled portions may be easily applied to the valve-body or removed from it without disconnecting the fitting.

In the drawings, Figure 1 is a vertical sectional view of a thermostatic valve device embodying my invention, and Fig. 2 is a perspective view of the valve-piece and the multiplying power-transmitting connection.

The valve device consists of a suitable valve-body *a*, having the usual inlet *b* and

outlet *c*, a valve-piece *d* to control the thoroughfare, a thermostatically-actuated piece *e*, and a compound lever or multiplying connection *f* between the valve-piece and the 55 thermostatically-actuated piece, by which the movements of the thermostatically-actuated piece are suitably multiplied in the valve-piece.

In the construction shown the valve-seat *g* 60 is carried by a removable open cage *h*, adapted to be seated upon the valve-body surrounding the outlet *c* and having a passage-way *i* communicating with the outlet and extending through the seat *g*. The upper part 65 of the cage carries a tubular extension *j*, extending upward within the tubular bonnet *k*, into which it may be screwed at the top, as shown. The expanding-piece *e* is supported at the top in the tubular extension, preferably by a shoulder *e'*, and its lower end is pivotally connected with one member of the compound or multiplying lever *f*. As shown, this multiplying lever connection *f* consists of two levers *m* *n*, of which the lever *m* is pivoted at one end, as at *m'*, to one side of the cage and at the other end, as at *m''*, to the lever *n*, between its fulcrum and free end, and the lever *n* is pivoted at one end, as at *n'*, to the other side of the cage and carries the 80 valve-piece *d* at its free end *n''*. The end of the expanding piece *e* is pivotally connected with the lever *m* between its fulcrum *m'* and point of connection *m''* with the lever *n*. With this construction any movement of the end 85 of the expanding piece *e*, due to elongation or contraction of its body through thermostatic action, will be multiplied in the free end of the lever *n* and in the valve-piece *d*, carried thereby, so that very small movements in the expanding piece will produce practical movements in the valve-piece. The elongation of the plug *e* when subjected to steam will close the valve-piece *d* upon its seat, and the contraction of the plug when subjected to air 90 or water of condensation will lift the valve-piece and open the valve passage-way.

I do not mean to limit my invention to the particular form or proportions of the compound or multiplying lever devices shown, 100 as they may be varied in many ways, according to the particular construction and arrange-

ment of the valve device and the amount of increase desired in the movement of the valve-piece.

5 A spring *o*, carried by the cage and bearing at its free end upon the compound lever mechanism, may be employed to take up lost motion and maintain the members of the lever mechanism in operative position to respond accurately to the movements of the 10 expanding member.

15 To remove the thermostatically-controlled parts, it is only necessary to unscrew the valve-bonnet *k* and remove it with the cage *h*. The cage may be detached from the valve-bonnet by unscrewing its tubular extension *j* from the bonnet.

20 To lift the cage from the outlet *c* for the purpose of blowing out the valve-body, it is only necessary to unscrew the bonnet-cap *p* and screw up the extension *j* in the bonnet to a sufficient extent to lift the base of the cage from the outlet *c*.

25 I do not mean to limit myself to an expanding member or piece of the character shown, or to the particular form of multiplying power-transmitting connections between the expanding member and the valve-piece, as these and other details of construction may be varied without departing from my invention.

30 What I claim as new, and desire to secure by Letters Patent, is as follows:

1. In a thermostatic valve device or fitting, the combination of a valve-body, having an inlet and an outlet, a cage removably secured 35 in the valve-body, a thermostatic expanding plug supported at one end within the cage and arranged to elongate and contract substantially in line with the valve-seat between the inlet and outlet, and a valve-piece suspended within the cage and movable with reference to the expanding plug and arranged to be operated by the free end thereof to close on the valve-seat when the plug elongates under thermostatic action.

45 2. In a thermostatic valve device or fitting, the combination of a valve-body, having an inlet and an outlet, a cage removably secured in the valve-body, fitting upon the outlet and provided with a valve-seat communicating 50 with said outlet, a thermostatic expanding plug supported at one end within the cage and arranged to elongate and contract substantially in line with the valve-seat in the cage, and a valve-piece suspended within the 55 cage and movable with reference to the expanding plug and arranged to be operated by the free end thereof to close on the valve-seat when the plug elongates under thermostatic action.

60 3. In a thermostatic valve device or fitting, the combination of a valve-body having an inlet and an outlet, a cage removably secured in the valve-body, a bonnet removably carried by the valve-body, an extension on the 65 cage projecting into the bonnet and carried

thereby, a thermostatic expanding piece carried by said cage, and a valve-piece supported in said cage, and movable with reference to said expanding piece and arranged to be operated thereby to control the outlet.

4. In a thermostatic valve or fitting, the combination of a valve-body having an inlet and an outlet, a cage in said valve-body having a valve-seat fitting upon the outlet of the valve-body and provided with a passage-way 75 communicating therewith, a bonnet removably carried by the valve-body, an extension on the cage projecting into the bonnet and being adjustably connected therewith to permit the adjustment of the cage and its 80 valve-seat, an expanding piece carried in the extension of the cage, and a valve-piece supported in the cage and movable with respect to the expanding piece and arranged to be operated thereby to control the passage-way 85 in the cage.

5. In the thermostatic valve or fitting, the combination of a valve-body, having an inlet and an outlet, a cage removably secured in the valve body, a valve-piece supported in the 90 cage and adapted to control the outlet, an expanding piece carried by the cage, a lever pivoted to the cage at one end and having the free end of the expanding piece pivoted thereto, a second lever pivoted at one end to the 95 cage and at the other end to the valve-piece and intermediately pivoted to the free end of the first lever.

6. In a thermostatic valve or fitting, the combination of a valve-body having an inlet 100 and an outlet, a cage in said valve-body having a valve-seat fitting upon the outlet of the valve-body and provided with a passage-way communicating therewith, a bonnet removably carried by the valve-body, an extension 105 on the cage projecting into the bonnet and being adjustably connected therewith to permit the adjustment of the cage and its valve-seat, an expanding piece carried in the extension of the cage, a valve-piece arranged to 110 control the passage-way in the cage, and multiplying levers carried by the cage and connecting the expanding piece and valve-piece.

7. In a thermostatic valve device or fitting, the combination of a cage adapted to be inserted in the valve-body and provided with a valve passage-way, a thermostatically-actuated part, a lever *m* pivoted to said cage and connected with said thermostatically-actuated part, a second lever *n* also pivoted to 115 said cage and connected with said lever *m*, and a valve-piece carried by said lever *n* and adapted to control the valve passage-way in said cage.

In testimony of which invention I have 125 hereunto set my hand.

CHARLES H. ATKINS.
